(57) **CLAIM**

The ornamental design for a smart watch band, as shown and described.

DESCRIPTION

FIG. 1 is a front perspective view of a smart watch band showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view thereof;

FIG. 9 is a partial bottom plan view taken from the viewpoint of the lines 9-9 in FIG. 2; and,

FIG. 10 is a partial top plan view taken from the viewpoint of the lines 10-10 in FIG. 2.

The dashed broken lines in the figures depict portions of the smart watch band that form no part of the claimed design.

1 Claim, 10 Drawing Sheets
